UNITED STATES PATENT OFFICE.

ELBERT ANDERSON, OF ANDALUSIA, ALABAMA.

MAIL-BOX.

1,105,869.

Specification of Letters Patent.

Patented Aug. 4, 1914.

Application filed May 3, 1913. Serial No. 765,306.

To all whom it may concern:

Be it known that I, ELBERT ANDERSON, a citizen of the United States, residing at Andalusia, in the county of Covington and State of Alabama, have invented certain new and useful Improvements in Mail-Boxes, of which the following is a specification, reference being had therein to the accompanying drawing.

10 This invention relates to mail boxes and has for its object the production of a simple and efficient means whereby the mail box may be automatically opened as the mail carrier passes the box so as to facilitate the 15 removal of mail articles or the delivery of such articles to the box.

A further object of this invention is the production of a simple and efficient box provided with a false bottom whereby the articles of mail contained within the box may be elevated to the top thereof so that the mail carrier or collector may easily obtain access to the interior of the box so as to remove articles therefrom.

20 25 With these and other objects in view, this invention consists of certain novel constructions, combinations and arrangements of parts, as will be hereinafter fully described and claimed.

30 This invention is illustrated in the accompanying drawings, wherein:—

Figure 1 is an end view of the apparatus. Fig. 2 is a central transverse section through the center of the mail delivering box. Fig. 3 is a central longitudinal section of the box. Fig. 4 is a side elevation partly in section of the trip mechanism for the box. Fig. 5 is a detail perspective of the false bottom used in connection with the present 40 invention. Fig. 6 is a transverse section through one of the guiding cleats coöperating with the false bottom.

By referring to the drawings, it will be seen that 1 designates the supporting standard which is anchored in the ground in the usual manner common to a supporting post, and this supporting standard 1 carries a mail box 2 at its upper end. This mail box 2 comprises an elongated body having a hinged top 3 which top is secured to the body by means of the hinge 4. A filler block 5 is positioned within the top 3 and this filler block is adapted to be engaged by the lifting arm 6 which arm is secured to 50 the box by means of the roller 7 which roller

travels in the slot 8 formed in the lifting arm 6. The lifting arm 6 is substantially an S-shaped member having an upturned inner end 9 and an upturned and outwardly extending end 10. The slot 8 extends longitudinally of the lifting arm 6 and as the same is swung it will be seen that the slot will allow the arm 6 to move inwardly of the box 2 so as to easily raise the top 3 thereof to enable the mail carrier to obtain 60 access to the interior of the box. A slot 11 is formed adjacent the roller 7 so as to allow the arm 6 to pass therethrough.

A pair of link members 12 are connected to the false bottom 13 and as the rear end 70 of the lifting arm 6 is pulled downwardly to the position shown in dotted lines, the cover of the box will be raised to the position shown in dotted lines in Fig. 2. The links 12 connect the top 3 and the false 75 bottom 13 so as to cause the false bottom 13 to be raised or elevated as the cover 3 is swung outwardly. The false bottom 13 is provided upon its end and sides with dove-tailed notches 14 which fit over the 80 dove-tailed guiding members 15 carried by the sides of the box. It will, therefore, be seen that these guiding members 15 will constitute an efficient means whereby the false bottom will be held in its correct position 85 so as to keep from binding as the same is elevated by means of the links 12.

A vertical sliding frame 16 is carried by the standard 1 and comprises a laterally extending foot 17 which foot is braced by 90 means of a diagonally extending brace 18. The outer end of the foot 17 engages the link member 19 by having its end fitting in the aperture 20 formed in the center of the link. This link is pivotally connected at 95 its respective ends to the sections 21 of the trip member and these sections 21 are substantially channel-shaped in cross section having flanges 22 to constitute a guide for the wheel of the vehicle and prevent the 100 wheel from falling over the sides of the trip member as the wheel passes over the same. It will be seen that as the vehicle passes over the trip member as illustrated in Fig. 1, the frame 16 will be pulled downwardly to the position shown in dotted lines, thereby swinging the arm 6 so as to throw the cover 3 upwardly. At the same time the false bottom 13 will be raised or elevated to the position shown in dotted 105 110

lines in Figs. 1 and 2, and the mail carrier will be enabled to obtain easy access to the box without dismounting from the vehicle.

From the foregoing description, it will be seen that a very simple and efficient device has been produced whereby the mail box will normally be held in a closed position but as the mail carrier passes the same the box will be automatically opened by means of the trip mechanism so as to enable the carrier to deliver mail to the box or receive mail therefrom.

Having thus described the invention, what is claimed as new, is:—

15 1. In a device of the class described, the combination with a supporting standard, of a trip mechanism, a box carried by said standard, a cover hinged to said box, a cover elevating arm secured to said box and comprising a substantially S-shaped member provided with a longitudinally extending slot, a roller supported upon said box and traveling in said box for facilitating the longitudinal movement of said arm relative

to the sides of the box, operating means 25 engaging said arm for raising said cover as the same is swung upon said box, a false bottom carried by said box, means connecting said false bottom and cover for causing said false bottom to be raised as said cover 30 is swung.

2. A mail box comprising a body, a cover hinged to said body, a cover elevating arm secured to said box, said arm comprising a substantially S-shaped member provided 35 with a longitudinally extending slot, a roller supported upon said box and traveling in said slot of said S-shaped arm to facilitate the inward and upward movement of said arm, and means secured to said arm for 40 moving said arm inwardly and upwardly.

In testimony whereof I hereunto affix my signature in presence of two witnesses.

ELBERT ANDERSON.
